UNITED STATES PATENT OFFICE

WILLIAM P. BRIGHT, OF BETHLEHEM, PENNSYLVANIA

ADJUSTABLE DOOR JAMB

Application filed November 24, 1928. Serial No. 321,667.

This invention relates to door and window frames having jambs adjustable for the purpose of making a proper fit with the striking edge of the door in cases where the door has either shrunk or swollen beyond the size when it was first fitted and hung in its door frame.

The main object of the invention is to provide a door frame of this type with adjustable parts which can be readily and cheaply made when the door frame is under process of manufacture.

Another object of the invention is to provide a door frame of this type in which the adjustable jamb will not weaken the striking stile to any great extent and which may be readily adjusted by means of the ordinary screw driver.

Other objects of the invention will become apparent as the detailed description thereof proceeds.

In the drawings:

Figure 1 is an elevation of a door hung in its frame with parts of the architrave on the striking side of the frame removed and the adjustable parts of the jamb shown in section to illustrate the operation of the several parts of the invention;

Figure 2 is a vertical section on the line 2—2 of Figure 1, illustrating the adjustable jamb in elevation and the stop strip thereof in elevation and broken away;

Figure 3 is a horizontal section taken on the line 3—3 of Figure 1;

Figure 4 is a fragmentary vertical section illustrating a modified form of the means for adjusting the adjustable jamb;

Figure 5 is a fragmentary vertical section of another modified form of the jamb adjusting means; and

Figure 6 is an exploded perspective of one of the adjusting screws and spring washers adapted for use therewith.

Referring to the drawings:

The reference character 1 designates a door hinged to a frame 2 by means of the usual hinges 3 and 4. The hinged side and the top of the door frame may be of any usual construction. The stile 5 at the striking side of the door frame is constructed somewhat differently in order to provide for the adjust-

ing of the door receiving recessed part of the frame to accommodate properly the door as it varies in width according to weather conditions.

The stile 5 is made up of a solid part 6 secured in any suitable manner to a stud 7. The part 6 extends evenly with the inner edge 8 of the stop strip 9 and forms with the stud 7 a deep recess 10 in which the adjustable jamb 11 is slidably mounted.

The door frame may be provided with the usual architrave trim 12 and 13. The trim 13 is securely fixed to the stud 7 and extends beyond this stud toward the striking edge of the door and forms with the part 6 a channel-like recess in which the part 11 slides.

At the bottom of the recess 10, the stud 7 is provided with a metal plate 14 which is tapped at intervals to receive the screw-threaded shanks 15, projecting with free sliding fit into bores 16 formed in the stud 7.

The back of the sliding jamb 11 is provided with a metal plate 17 and this plate is provided with apertures 18 in alignment with bores 19 formed in the sliding jamb 11. Countersunk cups 20 are located in corresponding countersinks 21 flush with the face of the jamb 11 and are adapted to receive the head 22 of the adjusting screws.

In the form of the invention illustrated in Figure 3 the screws are bored, just where the shank projects through the plate 17, and a cotter pin, or similar device, 23 is secured therein to form an abutment against the back of plate 17 which will prevent removal of the screws from the jamb, and also serves to move the jamb outwardly from the stud 7 when the screw is correspondingly adjusted.

The pins 23 may be omitted and springs 24 may be placed around the screws and between the plates 14 and 17 to provide for adjustment of the jamb 11 outwardly from the stud 7. This modification is shown in Figure 4.

In the modification shown in Figure 5 the screws 25 are provided with annular recesses 26 adapted to receive split spring washers 27 to form holding abutments for the screws against the back of the plate 17.

The springs 24 are not necessary wherever

the pins 23, or washers 27, are employed. However, it is preferable to use them in order to prevent possibility of rattling of the parts and separation thereof.

It will be apparent from Figure 3 of the drawings, that the parts 6 and 7 may be made in one piece at the factory, and that the adjustable jamb 11 may be readily assembled with the one piece part 6 and 7 and with the face thereof alined with the face of the part 6. This adjustable jamb will then present no appearance different from the usual jamb except for the showing of the head of the screws and cups which are seated flush with the face of the adjustable jamb and provide for the adjustment thereof.

The saddle or carpet strip 28 may be cut under the bottom end of the adjustable jamb so as to prevent the showing of the space between the saddle and the jamb, when the latter may be adjusted toward the stud 7. However, the adjustment of this jamb is usually so slight in one direction or the other that the saddle may be fitted between the door jambs in the usual manner.

The operation of the invention will be apparent from the drawings and need not be described in detail herein.

While I have parts 6, 7 and 9 as separate pieces assembled to form the striking stile of the door, it must be understood that these separate elements may be formed integrally with each other in order to facilitate factory assembling of the striking stile and the adjustable jamb. I have shown these elements section lined in the same direction to accentuate this idea and will claim it accordingly.

What I claim is:

A door frame having at the striking side, a stile provided with a groove, a jamb slidably seated in said groove, screws arranged at intervals along said jamb extending from the front, depth-wise through said jamb and threadedly engaging the bottom wall of said groove, stops on said screws behind said jamb for pushing the latter outward when said screws are backed, and springs on certain of said screws between said jamb and the bottom wall of said groove for taking up looseness between said jamb and the heads and stops of said screws.

In testimony whereof I affix my signature.
WILLIAM P. BRIGHT.
